FASTENING SLEEVE FOR BAND STRAPPING

Anton Latz, Kolin-Hohenberg, Germany

Application June 28, 1950, Serial No. 170,749
In Germany July 20, 1949

1 Claim. (Cl. 24—23)

1

With steel band strappings for packed articles of any kind, fastening is generally effected by a sleeve which encloses the overlapping ends of the band or strip. The pull-resisting fastening is achieved by mutual deformation of the sleeve and the ends of the band.

When a so-called closed sleeve is employed, this is first of all slipped over the steel band, whereupon, the free end of the band is passed around the package and then also passes through the same sleeve. The common deformation of band and sleeve is effected in a sealing device.

The object of the present invention is to simplify the slipping over of the sleeve or the guiding of the free end of the band into the sleeve. This is of particular importance, because packing operations are frequently carried out in restricted spaces and under bad light and, in addition, because the sleeve is to enclose the ends of the steel band as tightly as possible.

According to this invention, the introduction of the end of the band into the sleeve is facilitated because the latter is expanded on its flat upper side and/or its lower side at one or both ends. The end edges of the sleeves which are bent down may at the same time serve as the guide when pushed laterally into the sealing device.

Some embodiments of the invention are illustrated, by way of example, in the drawing, wherein:

Fig. 1 shows the fastening of a steel band strapping in the completed condition and includes a broken line showing of a sealing device providing guide grooves;

Fig. 2 is a side elevation of the fastening sleeve before the stamping thereof;

Fig. 3 is an end elevation of the sleeve alone;

Fig. 4 shows another form of the fastening sleeve in longitudinal section, on the line 4—4 in Fig. 5 and combined with a sealing device;

Fig. 5 is a corresponding end view of the sleeve alone;

Fig. 6 is yet another form of the sleeve, also in longitudinal section on the line 6—6 in Fig. 7; and

Fig. 7 is a corresponding end view.

Referring to Fig. 1, the two ends 10a and 10b of the annularly-closed steel band 10, which is wound around a package, are fastened by a sleeve 11 by the margins of the latter, those portions of the ends 10a and 10b of the steel band which extend into the sleeve 11 being provided with tongue-like cuts 12 which are bent downwardly out of the plane of the sleeve 11. The upper surface of the sleeve is rounded at its open end edges

2

11a, such rounding preferably being arcuately about its centre point. In this way, the insertion of the sleeve 11 into the guide groove of the sealing device (shown by dotted lines 14 in Fig. 1) is greatly facilitated and binding is prevented. It is impossible for the sleeve to become jammed between the walls 14 of the guide groove, both when the walls of the grooves 14 extend at right angles to the longitudinal direction of the band 10 or at an angle thereto.

If, with this construction, the upper part of the steel band is indented from above by a straight stamping knife at the point 15, then that portion of the steel band lying therebeneath can everywhere yield resiliently downwards except where the projecting lower edge of the sleeve serves as a firm support up to a certain degree. If the lower layer of the band 10 should be lightly scored thereby over a short distance, this cannot have a harmful effect on the complete security of the strapping, since the weakest transverse section is always to be looked for within the sleeve, where the marginal cuts 12 are disposed.

If the sleeve 11 is initially manufactured as shown in Figs. 2 and 3 of the drawing, in which it is expanded in trumpet-fashion on its flat sides by bending up and bending down the free longitudinal edges 11b and 11c, respectively, this greatly facilitates the introduction of the free end of the band into the sleeve. This advantage is produced independently of whether the ends 11a of the sleeve are arcuate, as shown in Figs. 1 and 2 of the drawing, or whether they are made with straight edges, which has been customary in the past. The expansion at only one end is sufficient in certain cases. However, if the sleeve is made symmetrical by expanding both open ends, the advantage is obtained that the band 10 can be introduced into the sleeve 11 from either side at will.

With the trumpet-like expansion of the sleeve 11 as shown in Figs. 2 and 3 of the drawing, the walls of guide groove of the sealing device for the upper and lower edges 11b and 11c in the vertical direction can accordingly be arranged further away from one another than hitherto. It is clear that this greatly facilitates the introduction of the steel band with the sleeve into the guide groove of the sealing device. If the sleeve is guided with the bent-up end edges of its upper side and if these bent-up portions are pressed flat over their whole extent in the deformation of the sleeve which follows, then any guiding action into the sealing device ceases with the deformation, so that the lifting of the device from

3
the finished steel band strapping can take place without any difficulty.

In the case of the construction of the fastening sleeve 16 shown in Fig. 4 of the drawing, the end edges 16a on the supporting surface are bent angularly downwards. The angles formed at the edges 16a are made to run to a point as shown in Fig. 5. The insertion of the end of the steel band also presents no difficulty with this sleeve construction. On the other hand, the downwardly-turned end edges 16a allow guiding of the sleeve 16 when it is inserted laterally into the sealing device, the base plate of which is conveniently provided with suitably arranged guide grooves. In this manner, any displacement of the sleeve 16 during the tightening of the steel band is at the same time positively prevented. If the sealing device is so constructed that the angular portions 16a still have the same shape after the stamping or other deformation of the sleeve, then the pointed parts 16b are supported against the package and penetrate superficially into the latter in certain circumstances. In this way, it is made difficult for the sleeve to be deformed responsive to stresses transmitted thereto by the strap. It is most important, however, that the steel band strapping should be prevented from slipping laterally because of the penetration of the points 16b.

In the sleeve structure shown in Figs. 6 and 30 7 the ends 16c extend at an angle of about 90° from the plane of the bottom wall. The sleeve is guided into the sealing device substantially in the same manner as the sleeve illustrated in Figs. 4 and 5 and similarly fulfills the other requirements already mentioned before.

It should be mentioned that the invention is not restricted to the deformation of the sleeve 11 or 16 (and also of the ends of the band projecting into the sleeve) by marginal cuts 12. Fastening can also be achieved by any other stamp-

ing, punching, welding or like operation without departing from the basic feature of the invention.

I claim:

5 A sleeve-like strap seal adapted for mounting in guide means of a sealing device and for receiving the ends of a sealing strap extending about a package and for holding said strap ends in sealed position comprising sheet metal means forming a flat elongated tubular member having a side wall containing a longitudinal split, said tubular member being adapted to be operated on in the sealing device with the ends of said strap inserted therein to unite said seal with said strap ends, the opposite ends of said side wall of said tubular member adjacent said split extending angularly outwardly away from the axis thereof for the twofold purpose of facilitating the insertion of said strap ends into said tubular member and of facilitating insertion of said tubular member with said strap ends therein into guide means in said sealing device laterally thereof.

ANTON LATZ.
